CLAIM

I claim the ornamental design for a mobile digital TV set, as shown.

DESCRIPTION

FIG. 1 is a front view of the mobile digital TV set;
FIG. 2 is a back view of the mobile digital TV set;
FIG. 3 is a top view of the mobile digital TV set;
FIG. 4 is a bottom view of the mobile digital TV set;
FIG. 5 is a right view of the mobile digital TV set;
FIG. 6 is a left view of the mobile digital TV set;
FIG. 7 is a front perspective view with a supporting leg deployed;
FIG. 8 is a back perspective view with the supporting leg deployed; and,
FIG. 9 is a back perspective view without the supporting leg deployed.
